UNITED STATES PATENT OFFICE.

STEPHEN D. BAKER, OF NEW YORK, N. Y., ASSIGNOR TO THE HOTCHKISS, VAIL & GARRISON COMPANY, OF NEW YORK, N. Y., A CORPORATION OF NEW YORK.

DESIGN FOR A WATER-CLOSET BOWL.

50,674.

Specification for Design.

Patented May 1, 1917.

Application filed November 28, 1916. Serial No. 133,991. Term of patent 7 years.

To all whom it may concern:

Be it known that I, STEPHEN D. BAKER, a citizen of the United States, residing at New York city, in the county of New York and State of New York, have invented a new, original, and ornamental Design for Water-Closet Bowls, of which the following is a specification, reference being had to the accompanying drawing, forming part thereof.

The figure is a perspective view of the water-closet bowl taken from a point forward of the same, showing my new design.

I claim:

The ornamental design for a water-closet bowl, substantially as shown.

In testimony whereof, I affix my signature.

STEPHEN D. BAKER.
